METALLIC SHELVING AND THE LIKE

Alexander S. King, Philadelphia, Pa., assignor to
 David Lupton's Sons Company, Philadelphia,
 Pa., a corporation of Pennsylvania

Application March 17, 1932. Serial No. 599,528

3 Claims. (Cl. 211—71)

This invention relates to metallic furniture or supports, and especially shelving, for containers whose contents are desired to be accessible from the front. It is an aim of the invention to provide for supporting and maintaining such containers in convenient position for access, preferably sloping, so that their contents will not fall out or shift under the influence of gravity. Other objects and advantages that can be realized through the invention will appear from the description hereinafter.

In the drawing, Fig. I is a fragmentary side view, partly in vertical section, showing one preferred form of embodiment of the invention.

Fig. II is a fragmentary vertical section illustrating provisions for holding the container in position, on a larger scale than Fig. I.

Fig. III is a plan view of a shelf and its container-holding means.

Fig. I shows a portion of a vertical stack of shelves 10, one above another. They are supported by uprights 11, of channel, T, or other suitable cross-section, which have upward-directed tongues 12 punched and offset inward from their webs, for engaging end flanges 13 on the shelves. Preferably, the shelves 10 have their front and rear portions 15, 16 at an angle to one another, the front portions 15 sloping upward and forward as shown, and the rear portions 16 being substantially horizontal. The front shelf portions 15 have depending front flanges 17, channeled to receive labels or label-holders (not shown).

The containers 20 are shown as ordinary paper-board cracker boxes, resting sidewise on the sloping shelf portions 15. They are each of them equipped with the usual detachable metal frame 21 carrying a glazed swinging lid 22 suitably hinged or pivoted to the frame. The frame 21 affords a shoulder at the lower side of the box which coacts with holding means on the sloping shelf portion 15 to maintain the box in position on the slope 15. As shown in Figs. I and II, the frame 21 is of sheet metal, extending down around the box 20 and having its lower margin folded inward flat on itself at 23 so as to engage or interlock with the outward-folded portion 24 of the pasteboard wall of the box 20. As will readily be apparent from Figs. I and II, the lower frame member 21 is readily separable from the lower side of the box 20, to allow one or more clips 25 on the shelf portion 15 to hook and engage over the frame 21 and into the outward fold 24 of the card-board. These clips 25 are in the nature of inward-offset ears or tongues outstanding from the shelf 10, and may be formed by shearing and punching out the sheet metal of said shelf along a U-outline (see also Fig. III).

As shown in Figs. II and III, the root 26 of an ear 60 or tongue 25, where it joins the flat surface of the

shelf 10, is reinforced and stiffened with a sloping embossed rib 27.

When the box frame 21 has been slipped under the tongue 25 and pushed back as far as it will go, the shoulder at the edge of the frame 21 engages against the shoulder or offset 26 at the root of the tongue 25, which limits the rearward movement of the box 20 and assures a definite position of its front (as represented by the lid 22) relative to the front shelf edge 17, regardless of just how deep said box may be. The outstanding tongue 25 prevents accidental disengagement of the shoulder afforded by the frame 21 from the shelf shoulder 26. However, the box 20 can be very easily pulled forward so as to disengage and free its frame 21 from the tongue 25, when it is desired to remove it from the shelf 10.

Having thus described my invention, I claim:

1. A shelf of the character described for forward-opening containers, comprising front and rear portions extending at an angle to one another and having end flanges adapted to hook behind supporting clips and having on its front portion outstanding ears for holding a container in position thereon when the shelf is mounted with said front portion sloping rearward.

2. A structure of the type described comprising uprights of standard section having integral upwardly-directed tongues offset inward therefrom for support of removable shelves, each said shelf embodying front and rear portions extending at an angle to one another with end flanges adapted to hook behind the upright tongues aforesaid and outstanding on its front portion clips for holding a container in inclined position when said shelf is mounted with its front portion sloping rearward.

3. A structure of the type described comprising uprights of standard metal sections having integral upwardly-directed tongues offset inward from a web portion thereof for supporting removable shelves, each said shelf being of sheet metal and embodying front and rear portions extending at an angle to one another with end flanges adapted to hook behind the upright tongues aforesaid, said shelf also embodying outstanding clips on its front portion for holding a container in inclined position when the shelf is mounted with its front portion sloping rearward, and each shelf clip being in the nature of an offset tongue struck from the sheet metal shelf along a U-outline with the root portion reinforced by a sloping embossed rib.
